UNITED STATES PATENT OFFICE.

HENRY WAVERLY JOHNSON, JR., AND THOMAS CALVIN COFER, OF NORFOLK, VIRGINIA.

DESIGN FOR A BADGE.

No. 38,268.

Specification for Design.

Patented Oct. 9, 1906.

Application filed June 28, 1906. Serial No. 323,965. Term of patent 3½ years.

To all whom it may concern:

Be it known that we, HENRY WAVERLY JOHNSON, Jr., and THOMAS CALVIN COFER, citizens of the United States, residing at Norfolk, in the county of Norfolk and State of Virginia, have invented a new, original, and ornamental Design for Badges, of which the following is a specification, reference being had to the accompanying drawings, in which—

Figure 1 is an obverse view of the badge, and Fig. 2 a reverse view thereof.

We claim—

The ornamental design for a badge as shown.

HENRY WAVERLY JOHNSON, JR.
THOMAS CALVIN COFER.
